UNITED STATES PATENT OFFICE.

FREDERICK A. VOLLBRECHT, OF DETROIT, MICHIGAN, ASSIGNOR TO INDUSTRIAL ELECTRIC MFG. COMPANY, OF DETROIT, MICHIGAN, A CORPORATION OF MICHIGAN.

TOASTER.

1,213,981.

Specification of Letters Patent. Patented Jan. 30, 1917.

Application filed June 19, 1916. Serial No. 104,386.

To all whom it may concern:

Be it known that I, FREDERICK A. VOLLBRECHT, a citizen of the United States of America, residing at Detroit, in the county 5 of Wayne and State of Michigan, have invented certain new and useful Improvements in Toasters, of which the following is a specification, reference being had therein to the accompanying drawings.

This invention relates to electric heating 10 devices, such as toasters, and refers more particularly to an improved construction of electric toasters of that type in which the electrical resistance element is positioned between opposed grids.

Among the objects of the invention are to provide a construction in which the electrical resistance unit and preferably also the protecting grid can be constructed and 20 assembled as a separate unit; to so construct and arrange this unit and the frame that the unit and its terminals are held in position in the frame by a simple clip arrangement, the clips being preferably formed by lugs 25 struck inwardly from the end walls of the frame; to provide an improved construction of frame, and mounting, and reinforcement for the novel resistance unit; to provide a construction which can be economically 30 manufactured and assembled; and in general to provide an improved and simplified construction of the character above referred to.

The invention further resides in such features of construction and arrangements and 35 combinations of parts as will more fully hereinafter appear.

In the drawings: Figure 1 is a side elevation of an electric toaster embodying my invention. Fig. 2 is an end elevation of the 40 construction shown in Fig. 1. Fig. 3 is a cross section on the line $x-x$ of Fig. 1.

Describing in detail the particular construction shown in the drawings, A designates the toaster frame which comprises a 45 base B, a top C, and end up-rights D and E. At their upper and lower ends the up-rights D and E are each provided with flanges F and G respectively. The latter is riveted 50 or otherwise directly secured to the base B but the upper flanges are preferably secured to the top by rivets or other securing members, each extending through an offset shoulder H. This arrangement rigidly attaches 55 the top to the flanges of the end up-rights

but acts as a heat insulation between the connecting members. A similar insulating arrangement is maintained between the base B and the supporting legs J.

In the present construction the electrical 60 resistance unit K and the supporting grid L are formed as a unit which can be manufactured separately and assembled and held in position in the frame in the manner hereinafter described. This resistance and grid 65 unit comprises a pair of notched insulator members M and M' around which is wound a flat resistance wire N.

Each of the insulator members M and M' is formed of two layers of mica or other 70 suitable material, and between these layers there is interposed a reinforcing member O which is U-shaped in cross section and of lesser width than the insulator members. This reinforcing member and the insulator 75 members are held in position at the upper end by rivets P which extend through the insulator members and the reinforcement and clamp the same between the flanges P' and P' of a pair of angle bars Q. The other 80 flanges of these angle bars are provided with apertures Q² through which the upper ends Q³ of the grid bars Q⁴ extend. The lower ends of the grid bars extend through apertures Q⁵ in angle or Z-bars R and R'. The 85 vertical flanges of these Z-bars are secured to the reinforcing member and the insulator members by rivets or other suitable means. The construction as so far described 90 comprises the resistance and grid unit which can be manufactured and assembled separately from the frame.

For attaching the resistance unit and grid member to the frame, I preferably employ a simple and novel arrangement in which lugs 95 S and S' are struck in from the end up-rights D and E and are locked over the ends of the up-right flanges of the angle bars. After the unit is secured in place relative to the frame as above described the holding 100 members T and T' are engaged with the apertures T² in the end up-rights of the frame. At one end the holding members are provided with suitable operating handles T³ and T⁴ while at the opposite end there is 105 sleeved upon the wire of the holding member, a spring U which has a return-bent end U' adapted to catch over the edge of the end up-right, and a second return-bent portion U² adapted to catch under the offset portion 110

U³ of the holding member. This spring arrangement serves to resiliently press the holding members against the toast or other article engaging the grid and also serves to prevent longitudinal displacement of the holding members.

Suitable terminals V and V' are employed, these terminals being clamped to the lower portion V² of the U-shaped reinforcement. The ends of the flat resistance wire N are connected to these terminals and extend upward between insulator plates W and W, and from there one end passes through an aperture W³ in the lower end of one of the 15 insulator members. The wire is then wound around the notched insulator member M so as to be positioned in the notches X thereof and at the upper end of the insulator member M passes through an aperture Y and a 20 corresponding aperture Y' onto the insulator member M'. From here it is wound spirally in the notches X' of the insulator member M' until it reaches the aperture in the other insulator member from which it 25 passes, between the insulator plates W, back to the other terminal.

It will be noticed that a toaster constructed as above described has a minimum 30 number of parts and that the number of operations in manufacturing and assembling it is also reduced to a minimum. The construction, however, is one which has great 35 rigidity, since the lugs S and S' are arranged to bear against both the vertical and horizontal flanges of the angle-bars and thus hold the unit from either vertical or lateral movement relative to the frame. This novel arrangement also permits the 40 use of a heating unit from which there is direct radiation of the heat to the toast or other article to be heated. The invention however is not limited to the particular use mentioned nor to the details of construction, except as specified in the appended 45 claims.

What I claim as my invention is:

1. The combination with a frame having end up-rights, of an electrical resistance unit having angle shaped members at its upper 50 and lower ends, and securing lugs extending inwardly from said up-rights and engaging said angle shaped members.

2. The combination with a frame having spaced walls, of a flat electrical resistance

unit positioned between said walls and provided with a transverse flange, and means for holding said unit in fixed relation to said frame comprising lugs struck inwardly from said spaced walls and extending adjacent the transverse flange and into locking engagement with edge portions of the resistance unit.

3. The combination with a frame having end up-rights, of an electrical resistance unit having reversely positioned angle bars 65 at its upper and lower ends, and means for holding said unit in fixed position in said frame comprising lugs extending inwardly from the up-rights and engaging the vertical flanges of said angle bars and positioned 70 adjacent the horizontal flanges thereof.

4. The combination with a frame having end up-rights, of an electrical resistance unit comprising a pair of flat insulator members, a resistance wire wound on the outside of 75 said insulator members, reinforcement members positioned inside of the insulator members, a pair of angle bars having depending vertical flanges secured upon opposite sides of said insulator member, and lugs extending 80 inwardly from the end uprights and clamped against said vertical flanges, just beneath the horizontal flanges of the angle bars.

5. The combination with a frame having 85 spaced walls, of a combined electrical resistance unit and grid member comprising a wound electrical resistance unit having at its upper and lower ends reversely positioned pairs of angle bars, secured thereto, 90 grid bars extending through the other flanges of said angle bars, and means engaging said angle bars for holding said resistance and grid unit in position in said frame.

6. The combination with a frame, of an 95 electrical resistance unit supported therein, said unit comprising a pair of notched insulator strips of double thickness, a U-shaped reinforcing member of lesser width than the insulator strips positioned between the layers 100 of the insulator strips, an exposed resistance wire wound around the insulator strips and engaging in the notches thereof, and metallic reinforcing members secured at the opposite ends of said strips.

In testimony whereof I affix my signature.

FREDERICK A. VOLLBRECHT.
